UNITED STATES PATENT OFFICE.

JEROME BACON, OF OSHKOSH, WISCONSIN.

MECHANICAL MOVEMENT.

SPECIFICATION forming part of Letters Patent No. 315,378, dated April 7, 1885.

Application filed January 29, 1885. (No model.)

To all whom it may concern:

Be it known that I, JEROME BACON, a citizen of the United States, residing at Oshkosh, in the county of Winnebago and State of Wisconsin, have invented certain new and useful Improvements in Mechanical Movements; and I do declare the following to be a full, clear, and exact description of the invention, such as will enable others skilled in the art to which it applies to make and use the same, reference being had to the accompanying drawings, and to letters or figures of reference marked thereon, which form a part of this specification.

Figure 1 of the drawings is a face view of my device. Fig. 2 is an edge view of the same, and Fig. 3 is a detail view.

This invention has relation to mechanical powers for driving double-geared machines; and it consists in the construction and novel arrangement of devices, all as hereinafter set forth, and pointed out in the appended claims.

In the accompanying drawings, the letter A designates the end of an ordinary wringing-machine, to which my invention is represented as applied.

B indicates the upper shaft or journal, having the gear-wheel C, which engages the gear-wheel D of the lower shaft, E.

F is a brace applied by its upper end on the shaft or journal outside of the gear, and by the lower end to the edge of the tub or other bearing. This brace is designed to steady the machine at the operating side during the action of the lever.

G is the operating-lever, which is designed to be pivoted on the lower shaft at H. It is provided at its lower end just above the pivot-bearing with a pivoted pawl, K, which is adapted to engage a ratchet, L, on the lower shaft to turn said shaft in the direction indicated by the arrow when the lever is pushed upward from the horizontal to the vertical position. This lever works through the arc of a quarter of a circle, and when it is depressed from the vertical the pawl K is disengaged from the ratchet L and moves backward on the same for a fresh purchase.

To the lever is pivoted the arm S, the outer end of which is bifurcated or branched, and provided with the lateral pivoted links V, which extend inward from the ends of the branches on opposite sides of the gear C to the

upper shaft or journal, B, on which said links are also pivoted. The joint at which the branches of the arm S are pivoted to the links V also provides a pivot-bearing for the reversible pawl Z, which is designed to engage the teeth of the gear-wheel C. When in direct working position, this pawl extends inward, so that it acts in an opposite direction from the lever-pawl, serving, however, to turn the upper wheel, C, in the direction indicated by the arrow, which is the same direction in which said wheel is turned by the action of the lower wheel when the latter is operated by the lower pawl, K. When the lever is depressed, the pawl Z is in direct action, and when said lever is raised the pawl Z slides back on the gear-wheel for a new engagement.

In order that the lever G can be raised to the perpendicular, it is formed with a bend, a, whereby it is enabled to span the upper shaft or journal, B, which would otherwise form an obstruction. This bend forms the stop at the end of the rise of the lever. The lever is also provided with a lug-stop, b, designed to engage a shoulder or bearing, c, of the arm S when said lever has reached the horizontal, in order to prevent further movement in this direction.

To the body of the arm S, and projecting outward or toward the elbow-joint d, is secured a flexible tongue, T, preferably made of rubber, which is designed to serve as a spring to cause the pawl Z to act promptly and quickly when the lever is rapidly worked. This tongue also serves to prevent the pawl from being thrown backward casually and reversed during the work. It, however, enables the operator to easily reverse the pawl, which yields, however, sufficiently for this purpose when the pawl is turned outward to engage the wheel C in the reverse direction to back the machine. In the reversing operation the lower pawl is turned up out of engagement with its ratchet.

What I claim, and desire to secure by Letters Patent, is—

1. The combination, with the shafts B and E, the engaging wheels, and the ratchet on lever-shaft, of the main lever pivoted on the lower shaft and the stop bent at a to span the upper shaft, the lower pawl, K, the arm S, its links V, and the upper pawl, Z, pivoted at the elbow-joint, substantially as specified.

2. The combination, with the shafts and their engaging gear-wheels, and the ratchet on the lever-shaft, of the lever G, having the lower pawl and provided with the elbow-arm, and 5 links having at the joint an upper pawl, the stop-lug on the lever, and the stop shoulder or bearing on the arm, substantially as specified.

3. The combination, with the main lever having a pawl at its lower end, and the engaging wheels and ratchet, of the bifurcated arm, the links connected to the branches of this arm, and the pawl pivoted at the joint of said links and arm, substantially as specified.

4. The combination, with the upper shaft or 15 journal, the lower shaft, and the engaging gear-wheels mounted on these shafts, of the main operating-lever pivoted on the lower shaft, and having a lower pawl operating a ratchet to turn said shaft, the arm pivoted to said le-

ver and having links connected to the upper 20 shaft, the spring, and the upper pawl pivoted at the elbow-joint, substantially as specified.

5. The combination, with the upper shaft or journal, the lower shaft, and the engaging gear-wheels mounted on these shafts, of the main 25 operating-lever pivoted on the lower shaft, and having a lower pawl operating a ratchet on said lower shaft, the arm pivoted to said lever, its links, and the pawl engaging the upper gear-wheel, and a steadyng-brace extending 30 from the upper shaft or journal downward to a bearing, substantially as specified.

In testimony whereof I affix my signature in presence of two witnesses.

JEROME BACON.
